UNITED STATES PATENT OFFICE.

JOHN R. HARRIS, OF CHARTIERS TOWNSHIP, ALLEGHENY COUNTY, PENNSYLVANIA.

INSULATOR.

1,302,158.

Specification of Letters Patent. Patented Apr. 29, 1919.

Application filed July 11, 1917. Serial No. 179,841.

To all whom it may concern:

Be it known that I, JOHN R. HARRIS, a citizen of the United States, and residing in the township of Chartiers, in the county 5 of Allegheny and State of Pennsylvania, have invented or discovered new and useful Improvements in Insulators, of which the following is a specification.

My invention consists in certain new and 10 useful improvements in two part insulators or split knobs used for electrical wiring.

In the use of two part insulators for securing wires in place, especially where the insulators must be installed in locations difficult of access, considerable trouble is experienced in keeping the insulator or its parts in proper position to receive and secure the wire in proper alinement. Thus the wire groove in the base or cap and base of 20 the insulator must be turned into the proper position to receive and hold the stretched wire, and this adjustment is very difficult where the workman has a cramped or awkward space to work in or where the light is 25 poor, as is frequently the case where wiring is being done under a floor which must be disturbed as little as possible.

I overcome these difficulties by mounting the insulator on the nail or other attaching 30 member in such a manner that it will not rotate thereon, but when the nail is once started into the joist or other support in the proper manner, the wire may be inserted and the nail driven home with the positive assurance 35 that the wire groove or grooves will maintain the proper position in relation to the stretching of the wire. Where the registration of the cap with the base is not important, the base alone may be non-rotatively 40 mounted on the nail, but where the groove in the cap must register with the groove in the base, both the cap and base are so mounted on the nail that they cannot rotate thereon but their grooves will always 45 maintain the desired relative positions.

I also provide new and improved means for maintaining the base and cap in proper assembly during shipping, so that no sorting of parts and matching the same on the 50 job is required, but the insulator may at once be erected in place with but little care and attention.

In the accompanying drawings, which are merely intended to illustrate the principles 55 of my invention without limiting the scope of the same to the construction shown, Fig-

ure 1 is a side elevation showing my improved insulator with the attaching element started into the joist or other support and the base and cap separated for the introduction of the wire. Fig. 2 is a longitudinal section of the cap and base with the attaching element driven home into the joist so as to secure the insulator in place with the wire clamped between the cap and base, the wire 60 being omitted for the sake of clearness. Figs. 3, 4 and 5 are cross sections showing various forms of attaching members and holes through which they pass, illustrative of various embodiments of my invention, 65 such sections being taken along the dotted line III—III in Fig. 2. Fig. 6 is a side elevation of an insulator showing means for holding the cap and base in proper assembly during shipping or before installation 70 on the job. Fig. 7 is a similar view showing a modification, and Fig. 8 is a butt end view of the latter.

The following is a detailed description of my invention as illustrated in the drawings. 80

A represents the base of a two part insulator: B its cap, and C the nail or other element by means of which the insulator is mounted in place. D represents a joist or other support to which the insulator is to be 85 firmly attached with the electrical wire, not shown, clamped between its cap and base. 1 represents the wire groove which extends transversely of the outer end of the base at one side of its axis, and in the drawings I 90 have shown the cap provided with a similar groove 2 which must register with the groove 1 to properly engage the wire. I have shown the outer ends of both the base and cap countersunk in the usual manner but this 95 feature forms no part of my present invention. Both the base and cap are provided with axial holes or bores for receiving the attaching member or nail. Thus in Fig. 3, I have shown the axial hole 3 in the base A 100 of rectangular cross section and the nail C of proper cross sectional shape to fit in the same. Thus the base cannot rotate on the nail but the position of the former will depend upon the position in which the nail is 105 started.

In Fig. 4 I have shown the axial hole in the base and the nail of triangular cross sectional shape, while in Fig. 5 said hole and nail are shown as of oblong cross sectional 110 shape. It is evident that any eccentric form of hole and nail may be adopted which will

assure the prevention of the rotation of the base on the nail.

Where the cap as shown in Figs. 1, 2, 6 and 7, is provided with a transverse wire 5 groove, its axial hole 4 should be also of proper cross sectional contour to fit the nail or other attaching element in such a manner as to be held against rotating thereon.

To enable the parts of the insulator to be assembled on the nail or other attaching element at the factory, so as to be delivered at the job, ready to be installed, in proper relationship, and thus avoiding the loss of time otherwise required to sort out the bases 10 and caps, I mount on the nail C a small brad 5 which is seated in a small hole 6 bored transversely through the outer end of said nail, as shown in Fig. 6. Or I may provide two parallel or opposed face surfaces of the 15 nail with transverse slots 7 and slip over the nail a spring wire loop or clip 8. These fasteners 5 or 8 may be removed when the insulator is about to be installed. In Fig. 2 I show the nail flattened out outside the base 20 25 A of the insulator, as at 9. This forms a more secure method of holding the parts together but is more expensive to use.

It is evident from the foregoing that my invention is attended by numerous advantages. Thus it greatly expedites the work of putting up electrical wires, because but very little care is required to properly position and set the insulators, and the work can easily be done in a very cramped space 30 35 and with poor light, without impairing the accuracy and quality of the job. Since the insulators are properly placed and their grooves alined, slackening of the wire is avoided, and a firm grip is obtained on the wires 40 between the caps and bases of the insulators. The wire grooves are kept in proper position and automatically grip the wire with an even uniform engagement which prevents injury or chafing of the insulation and is not 45 susceptible to accidental loosening. These advantages are gained without increasing the cost of the insulators. The use of the fastening element on the inner end of the nail or other attaching element enables the 50 cap and base to be assembled in proper relation at the factory, thus saving much time on the job.

What I desire to claim is:—

1. A wire supporting knob of the character described, comprising clamping sections of suitable insulating material having parallel registering wire receiving grooves and axial rectangular apertures, and a rectangular nail which passes through the apertures in said sections. 60

2. A wiring knob of the character described, comprising clamping sections of suitable insulating material having parallel registering wire-receiving grooves, and axial apertures which are other than round and 65 a nail which passes through said apertures, which is of the same outline in cross section as said apertures.

3. A wiring knob of the character described, comprising clamping sections, of 70 suitable insulating material, having axial rectangular apertures adapted to receive a nail of a cross sectional shape corresponding to the shape of said apertures.

4. A wiring knob of the character described, comprising clamping sections, of 75 suitable insulating material having axial apertures which are other than round in cross section, and which are adapted to receive a nail of corresponding shape in cross section. 80

5. The combination with a two part insulator comprising a base and a cap, said base being provided with a transverse wire groove, both of said elements being provided with an axial hole and the axial hole in said 85 base being of non-circular cross section, and a member, adapted to attach said insulator to a support, extending through said axial holes and fitting the hole in said base, whereby said base is held against rotation in relation to said member, for the purpose set forth. 90

6. The combination of a two part insulator comprising a base and a cap, both of said elements being provided with an axial hole 95 of non-circular cross section, and a member, adapted to attach said insulator to a support, extending through said axial holes and fitting the same, whereby the parts of said insulator are held against rotation in relation to said 100 member, for the purpose set forth.

Signed at Pittsburgh, Penna., this 9th day of July, 1917.

JOHN R. HARRIS.
